UNITED STATES PATENT OFFICE.

NEIL CALLEN WARD, OF CHICAGO, ILLINOIS.

DESIGN FOR A DISPENSING APPARATUS OR ARTICLE OF SIMILAR NATURE.

57,457.

Specification for Design.

Patented Mar. 29, 1921.

Application filed May 17, 1920. Serial No. 382,194. Term of patent 14 years.

To all whom it may concern:

Be it known that I, NEIL CALLEN WARD, a citizen of the United States of America, residing at Chicago, in the county of Cook and State of Illinois, have invented a new, original, and ornamental Design for a Dispensing Apparatus or Article of Similar Nature, as shown in the accompanying drawing and described in the following specification.

The drawing is a perspective view of the liquid dispensing apparatus showing my new design.

I claim:

The ornamental design for a dispensing apparatus or article of similar nature as shown.

NEIL CALLEN WARD.

Witnesses:

C. J. HOWEL,
BESSIE RIGNEY.
